(No Model.)

J. F. MUNSIE,
MAN HOLE FOR UNDERGROUND ELECTRIC CONDUITS.

No. 426,206.

Patented Apr. 22, 1890.

Fig. 1.

UNITED STATES PATENT OFFICE.

JAMES F. MUNSIE, OF BROOKLYN, ASSIGNOR TO THOMAS L. COLES, OF NEW YORK, N. Y.

MAN-HOLE FOR UNDERGROUND ELECTRIC CONDUITS.

SPECIFICATION forming part of Letters Patent No. 426,206, dated April 22, 1890.

Application filed January 22, 1890. Serial No. 337,712. (No model.)

To all whom it may concern:

Be it known that I, JAMES F. MUNSIE, a British subject, residing at Brooklyn, in the county of Kings and State of New York, have 5 invented certain new and useful Improvements in Man-Holes for Underground Electric Conduits; and I do hereby declare the following to be a full, clear, and exact description of the invention, such as will enable others skilled in the art to which it appertains to 10 make and use the same.

My invention relates to certain new and useful improvements in man-holes for underground electric conduits, and has for its objects, first, to avoid explosions therein by keeping the man-hole chamber practically air and gas tight; secondly, to maintain said chamber in as dry a condition as possible; thirdly, to make suitable provision for insuring the 15 safety of the linemen entering the chamber; fourthly, to minimize or neutralize the injurious influence of induced currents from high-tension wires upon low-tension or battery wires passing through the man-hole chamber, 20 and, fifthly, to provide access to the man-hole chamber from the side and through a constantly-ventilated shaft or well furnished with dry air.

In attaining these several objects the invention 25 consists in the novel arrangement and construction of parts hereinafter described, and particularly pointed out in the claims forming a part of this specification.

In the accompanying drawings, Figure 1 30 represents a vertical cross-section, on a plane indicated by the line 1 1 of Fig. 2, of a man-hole chamber and its accessories embodying my invention. Fig. 2 represents a horizontal section of the same on a plane indicated by 35 the line 2 2 of Fig. 2. Fig. 3 represents an enlarged detail sectional view of the duct or tube frame shown in Fig. 1, and Fig. 4 represents a detail face view of the door or cover 40 over the entrance to the man-hole.

Similar numerals of reference indicate similar parts throughout the several views of the 45 drawings.

The man-hole chambers will be located in the usual manner at the intersection of cross- 50 lines of underground conduits, or at distrib-

uting and feeding points along said conduits, and will consist of two or more compartments, as 5 6, located one above the other and accessible only through an auxiliary shaft or well 7, the tops of both compartments being 55 entirely closed. The main walls of the compartments 5 6 are of brick or stone masonry, so as to insure solidity of structure, and are provided with an insulating-partition 8, built into said masonry, and consisting, preferably, 60 of wooden beams that have been impregnated by immersion or otherwise with boiled olive or other suitable oil. The upper compartment 5 serves for the passage of the low-tension or 65 battery wires supplying telegraphic or telephonic circuits and the like, and through the lower compartment 6, I prefer to pass the wires carrying currents high in tension and quantity from dynamos supplying electric lamps, &c.

In order to thoroughly insulate the two compartments 5 and 6 from each other, I separate them by an insulating-floor resting upon and supported by the beams 8, and consisting, preferably, of oil-impregnated boards 9 75 10, separated by an intervening filling 11, of tar-yarn, Chatterton compound, or the like. Each compartment is furthermore provided with an independent insulating-lining 12, separated from the walls of the compartment 80 by an intervening space, which I prefer to fill with an insulating water-proof and air-proof packing 13, preferably of Chatterton compound. By this arrangement of parts the compartments will be thoroughly insulated 85 from each other, so that no currents may be carried by conduction from one to the other, and each will be completely protected against access of air, gas, or moisture from the surrounding earth. The tendency of the 90 surrounding earth, especially during cold weather, is to condense moisture from the air within the man-hole chamber, said condensations gathering upon the inner walls and making them, to a certain extent, conductors of electricity. To absorb such moisture as formed, and prevent its deposit upon the compartment-walls, I provide in each compartment a pot or the like 14, containing unslaked lime, which 95 will take up the moisture, thereby keeping 100

the walls dry and preserving their insulating qualities.

In connection with the features of my invention thus far described, I wish to call attention to the following considerations: My object in surrounding the compartment-walls with an air-proof and water-proof filling is to protect the man-hole from all access of moisture and explosive gases from without. The said filling is completely adapted to such purpose. On the other hand, it is, when used alone, of some disadvantage, for the reason that it prevents the grounding of currents accidentally arising within the man-hole. Thus during the manipulation of wires within the man-hole it may happen that the uncovered ends of wires connected to the generator might come in contact with the said filling, and if such surface is moist the current will give a shock to the lineman should he inadvertently touch the moist surface. It becomes, therefore, of the highest importance to keep the walls of the man-hole as dry as possible, and also to secure the best possible insulation within the water-proof and air-proof filling, so that the walls shall be at all times of practically no conducting capacity. To the attainment of these ends I have therefore provided the compartments with the inner supplemental insulating-lining and have taken the necessary precautions of preventing the formation of moisture upon said lining by the introduction of unslaked lime within the compartment, these several provisions co-operating to produce a man-hole chamber that the lineman can enter with security.

In order to give access to the compartments 5 6, I provide in each a side opening leading 40 to the shaft 7, and having a door or cover 15, adapted to fit closely, so as to hermetically seal the opening. To this end I surround each opening with a frame 17, having a recess formed by the flange 16, within which recess is placed a gasket or other packing 18, and over this gasket is placed the door or cover 15, which is held in place by bolts 19, passing through the door or cover. By drawing up the nuts 20 on the bolts 19 the door or cover 50 will be firmly pressed against the gasket, thereby effecting an air-tight fit.

I will now describe my preferred manner of passing the wires or cables into and from the man-hole chambers. At 21 is indicated 55 what I term "duct" or "tube" frames, consisting, primarily, of a frame which is set into the masonry forming the compartment-walls, and is inclosed by the same, as shown more fully in Figs. 1 and 3. The duct 22 for the electric 60 wires or cables 23 passes into and through the frame 21 and fits the same closely. In Fig. 3 the numeral 24 indicates a tube-sheet fitted in front of the duct 22 and within the frame 21, through and into which the tubes 65 25 for the wires or cables pass. The frame 21 may, however, be omitted, if desired, and the tube-sheet may be fitted directly against

the masonry. The frame 21 is to be closely fitted within the masonry, and to that end it is provided, preferably, on both sides with 70 recesses 26, within which is placed a packing 27, surrounding the duct 22. A plate or cover 28 fits against the packing 27 and against the side 29 of the frame, being held tightly against the latter by the bolts or rivets 30, as shown. 75 By this means the passage of gas or moisture between the duct 22 and frame 21 is effectively guarded against. The requisite number of duct or tube frames and their described accessories is to be placed in each 80 compartment for the accommodation of the separate conduits leading into and away from said compartments.

In order to reduce the destructive effects of electric currents from atmospheric causes— 85 such as lightning shocks—I prefer to place a lightning-arrester 31 in proximity to the wires, said lightning-arrester being connected to the earth by an insulated conductor of large carrying capacity 32, leading to the grounded 90 rod 33; or, if preferred, the lightning-arrester may be connected to the duct-frame 21 for the same purpose.

When battery-wires for telegraphic and telephonic circuits pass through a man-hole 95 chamber in a parallel relationship to and in proximity to wires conveying currents high in tension and quantity for electric lighting and similar purposes, induced currents are 100 set up in the battery-wires, which induced currents interfere with the battery-currents and affect the proper working of the instruments. To neutralize or minimize this action, I interpose between the two sets of wires a conductor 53 of large carrying capacity, 105 consisting, preferably, of a metal plate located near the top of the lower compartment 6 and across the entire length of the man-hole, and through the walls of the same for a sufficient distance to be completely grounded at each 110 end. A closed parallel circuit, of which the earth forms the return, is thus interposed between the two sets of wires. This circuit acts as a protector to the battery-wires, and the induced currents that would otherwise be generated in the battery-wires are set up in said 115 protecting-circuit and dissipated in the earth.

I will now describe my preferred arrangement of well or shaft 7. At the lower part of said shaft I prefer to place a pot 34, containing unslaked lime to absorb moisture and assist in keeping the shaft dry. I desire to have a thorough circulation of dry air through the shaft, and to that end I provide the following arrangement: The top of the shaft is 120 covered by a perforated plate 35, as shown, and a stand-pipe 36 leads to the lower part or bottom of the shaft, said stand-pipe extending upwardly above the surface of the ground (preferably near the curb 37) to a height 125 greater than the plate 35, so as to create an upward draft through said pipe. The upper end of the pipe is provided with a hood to prevent the access of rain to its interior. By the

arrangement described air circulates through the shaft, preventing the accumulation of explosive gases therein and keeping the shaft in proper condition for the linemen to enter.

- 5 In order to prevent rain or drippings that may enter the perforated cover from reaching the bottom of the shaft, I place within the shaft a suitable removable partition or water-catch 38, which may be supported upon a bracket or ledge 39, or in any other suitable way, the partition being preferably bolted to the ledge upon a gasket 54 to make a water-tight joint. A pipe 40 passes from the water-catch to the sewer to carry away the water 15 that may collect upon the water-catch. I provide said pipe with a suitable trap 41 to prevent gas from entering the shaft from the sewer, and I also prefer to place a check-valve 42 in the pipe for additional protection.
- 20 In order that the circulation of air through the shaft may not be impeded by the water-catch 38, I perforate the same, as at 43, and cover said perforations with tubes or hollow cones 44, upon which I place caps 45, as shown.
- 25 By this means air is free to pass through the water-catch, while, as the hollow cones or tubes 44 project above its surface, water will not pass through the water-catch.

Within the shaft and below the water-catch 38, I locate a shelf 46, entirely covering the portion of the shaft below it. This shelf is removable, and upon its upper surface I spread or distribute unslaked lime, as shown. The air entering from above through 35 the hollow tubes or cones 44 is deprived of its moisture by contact with this unslaked lime, and passes in a dry state through the by-pass 47 to the bottom portion of the shaft.

Below the removable shelf 46, I secure a 40 ladder 48, whereby the linemen may readily reach the lower part of the shaft, after first removing the water-catch 38 and shelf 46.

In order that the air in the compartments 5 6 may be thoroughly purified before the 45 men enter the same, I place suitable air-taps or air-cocks 49 in the doors or covers 15, as shown. Before the men remove the cover or door they open these cocks or taps, so that fresh dry air from the shaft may enter the 50 compartments through one tap and escape through the other. Instead of the taps 49, any other suitable arrangement for opening and closing the air-apertures in the covers may be employed. After the air in the compartment has been purified the door or cover 55 15 may be lifted off and the linemen can enter with safety. A constant circulation of dry fresh air is kept up in the compartment and shaft while the linemen are at work by means 60 of the pipe 36. After the work is completed the cover, or door 15 is replaced and tightly sealed to prevent air or gas entering the compartment.

When the men are working in the shaft or 65 compartment, the pipe 36 may be used as a speaking-tube, by which to communicate with

the men without the necessity of a nearer approach.

Having thus described my invention, what I claim is—

1. A man-hole for underground electric conduits, provided with an air-proof and water-proof jacket, in combination with a moisture-absorbent for preventing condensations upon the inner walls of said jacket, substantially as described. 75

2. A man-hole for underground electric conduits, having low-tension or battery wires passing through its upper portion, and high-tension or electric-light wires passing through 80 its lower portion, in combination with a parallel conductor interposed between the two sets of wires to neutralize or minimize the effect of induced currents, substantially as described. 85

3. A man-hole for underground electric conduits, consisting of an upper compartment for the reception of low-tension or battery wires, and a lower compartment for the reception of high-tension or electric-light wires, 90 the said compartments being provided with air-proof and water-proof jackets, and being insulated against conduction from one to the other, substantially as described.

4. A man-hole for underground electric 95 conduits, in combination with a side shaft or well having an opening for communication with the man-hole, a cover or door for said opening, and ventilating devices in said door, substantially as described. 100

5. A man-hole for underground electric conduits, in combination with conductor-tubes entering said man-hole, a duct surrounding said tubes, a tube-sheet traversing said tubes, and an outer frame surrounding 105 said duct, substantially as described.

6. A man-hole for underground electric conduits, in combination with conductor-tubes entering said man-hole from an adjacent man-hole, and a tube-sheet receiving said 110 tubes, substantially as described.

7. A man-hole for underground electric conduits, in combination with a tube-sheet frame having a recess 26, containing a packing 27, plate 28, and duct 22, surrounded by 115 the latter, substantially as described.

8. The shaft 7, having perforated cover 35, in combination with the water-catch within the shaft, said water-catch having ventilating-openings, and means, substantially as described, for carrying away the water from said water-catch, substantially as described. 120

9. The shaft 7, having perforated cover 35, in combination with the perforated water-catch 38, said water-catch having hollow tubes 125 extending above the perforations in the water-catch, hoods upon said tubes, and means, substantially as described, for carrying water away from said water-catch, substantially as described. 130

10. The shaft 7, having perforated cover 35 and ledge or bracket 39, in combination with

the water-catch 38, resting on said ledge, a pipe leading from said water-catch to a sewer, and a trap or seal in said pipe, substantially as described.

5 11. The shaft 7, provided with perforated cover 35, in combination with the ventilating pipe 36, the water-catch 38 within the shaft, means, substantially as described, for carrying away the water from said water-catch, the 10 man-hole, and the door or cover separating said man-hole from said shaft, substantially as described.

12. The shaft 7, having perforated cover 35 and ledge 39, in combination with pipe 36, 15 connecting with the lower end of the shaft, the water-catch 38, resting on said ledge, a

packing between the water-catch and ledge, and a pipe leading from the water-catch to a sewer, said pipe being provided with a trap or valve, substantially as described. 20

13. The shaft 7, in combination with the pipe 36, leading from the bottom of said shaft, the water-catch 38, the shelf 46 below said water-catch, said shelf containing unslaked lime, and the by-pass 47, substantially as de- 25 scribed.

In testimony whereof I affix my signature in presence of two witnesses.

JAMES F. MUNSIE.
